UNITED STATES PATENT OFFICE.

SAUL DUSHMAN, OF SCHENECTADY, NEW YORK, ASSIGNOR TO GENERAL ELECTRIC COMPANY, A CORPORATION OF NEW YORK.

VACUUM DISCHARGE APPARATUS.

Application filed March 4, 1919, Serial No. 280,632. Renewed September 29, 1923.

My present invention relates to vacuum discharge devices and more particularly to devices of the type commonly known as electron discharge devices in which the operating current is entirely carried by means of negative electrons.

The object of my invention is to provide improved forms of construction for such devices whereby their operation will be rendered more reliable and efficient.

The novel features which I believe to be characteristic of my invention are set forth with particularity in the appended claims, the invention itself, however, both as to its construction and method of operation, together with the special advantages thereof, will best be understood by reference to the following description taken in connection with the accompanying drawing in which Fig. 1 is a perspective of one of my improved devices and Fig. 2 is a fragmentary view showing the electrode structure.

As indicated in the drawing, my improved device comprises an evacuated receptacle 1 in which are located a cathode 2 of filamentary form, a grid electrode 3 surrounding the cathode and an anode 4 surrounding both the cathode and grid. Leading-in conductors 5 and 6 which are sealed through the stem 7 supply heating current to the cathode and also serve to support the ends thereof. A supporting arm 8 has one end embedded in the stem 7 and extends axially in the tube, the middle point of the cathode 2 being secured to the opposite end thereof. The grid electrode 3 is in the form of a helical coil which may be made of wire which is so small and flexible that it would be incapable of maintaining itself in a desired position in the device. To overcome this difficulty two diametrically opposite supporting arms 9 and 10 are embedded in the stem and these arms are secured to the outside of each turn of the grid coil in any desired manner, preferably by welding. One of these arms is extended through the stem 7 and serves as a leading-in conductor for the grid electrode. By this construction it is possible to make the grid of wire of any desired size and also to provide a uniform spacing between the turns which will be maintained without any possibility of change during the operation of the device.

In the operation of devices of the type here involved, a large amount of heat is pro-

duced at the anode and the amount of energy which may be controlled is limited by the allowable heating of the anode. The capacity of the device may be greatly increased by providing a plurality of heat radiating surfaces upon the anode, which in the present case are in the form of fins 11 extending outwardly from the surface of the anode along the entire length thereof. The anode is made of sheet metal which is bent in such a way as to form an opening through the electrode adapted to contain another electrode or electrodes. In the present case the electrode is given a substantially cylindrical form with the fins 11 thereon as indicated. These fins provide a heat radiating surface having a surface area of the same order of magnitude as the surface area of the anode and permit the radiation from the anode of a much larger amount of heat than would be the case if no heat radiating surfaces were provided. From another viewpoint it permits the use of a much smaller anode for a device of a given capacity and thereby reduces the impedance of the device due to space charge.

The anode may be made of a single piece of sheet metal or of more than one piece as may be most convenient. It will be noticed that each of the fins is made up of two layers of the metal and that the supporting arms 12 are inserted between the two layers, the metal being pressed around these arms so as to closely embrace them. The supporting arms 12 are secured to a split cylindrical member 13 which surrounds the stem 7 and is held in position by means of a clamping bolt 14. A leading-in conductor 15 which is secured to the clamping bolt 14 serves to carry current from the anode and is sealed into the receptacle when the stem 7 is joined to the receptacle. By sealing this leading-in conductor in at the point indicated it is possible to operate the device at as high potentials as may be desired between cathode 100 and anode without impressing any large potential differences between any of the conductors which are sealed into the stem 7.

What I claim as new and desire to secure by Letters Patent of the United States, is,—

1. In a vacuum discharge device, an electrode having an opening therethrough, a plurality of heat radiating surfaces having a surface area of the same order of magnitude as the surface area of the electrode

- formed integrally therewith and extending outwardly therefrom, and a plurality of supporting arms secured to said heat radiating surfaces.
5. 2. In a vacuum discharge device, an evacuated receptacle, a plurality of electrodes within said receptacle, one of said electrodes having an opening therethrough with a plurality of heat radiating surfaces extending outwardly therefrom having a surface area of the same order of magnitude as the surface area of the electrode, a stem through which leading-in conductors for said electrodes are sealed, and a plurality of supporting arms carried by said stem, said supporting arms being operatively related to said heat radiating surfaces for supporting in the receptacle the electrode of which these surfaces form a part.
20. 3. In a vacuum discharge device, an evacuated receptacle, a cathode of filamentary form and a grid within said receptacle, an anode surrounding said cathode and grid, a plurality of heat radiating surfaces extending outwardly from said anode, said heat radiating surfaces having a surface area of the same order of magnitude as the surface area of the anode, a stem through which leading-in conductors for said cathode and grid are sealed, a plurality of supporting arms carried by said stem, said supporting arms being operatively related to said heat radiating surfaces for supporting said anode in the receptacle, and a leading-in conductor connected to said supporting arms and sealed into said receptacle at a point remote from that at which the leading-in conductors for the cathode and grid are sealed into said receptacle.
40. 4. In a vacuum discharge device, an evacuated receptacle, a cathode of filamentary form, an anode and a grid within said receptacle, a stem through which leading-in conductors for said cathode and grid are sealed, a clamping band embracing said stem, a plurality of supporting arms connected to said band, said supporting arms being secured to said anode and a leading-in conductor for said anode connected to said band and sealed into said receptacle at a point remote from that at which the leading-in conductors for the cathode and grid are sealed into said receptacle.
55. 5. In a vacuum discharge device, an electrode having an opening therethrough and a plurality of heat radiating surfaces extending outwardly therefrom along the entire length of the electrode.
6. In a vacuum discharge device, an electrode having an opening therethrough, said electrode being provided with a plurality of fins forming heat radiating surfaces, said fins being formed of two layers of metal and supporting arms for said electrode, said supporting arms being embraced by said fins.
7. An electron discharge device comprising a containing vessel having a neck, a stem having a flare joined to the neck of said vessel, electrodes supported by said stem and lead wires for said electrodes, certain of said lead wires being sealed in said stem and the remainder of said lead wires being sealed in between the flare of said stem and said neck.
8. An electron discharge device comprising a containing vessel having a neck, a stem having a flare joined to the neck of said vessel, electrodes supported by said stem, and a lead wire for one of said electrodes external of said stem and sealed in between the flare of said stem and said neck.
9. In a vacuum discharge device, an electrode having an opening therethrough and a plurality of heat radiating surfaces, said surfaces having an area of the same order of magnitude as the surface area of the electrode and extending outwardly from said electrode and in an axial direction with respect to the electrode.
10. In a vacuum discharge device, an electrode having an opening therethrough and a plurality of heat radiating surfaces extending outwardly therefrom and in an axial direction along the entire length of the electrode.
11. In a vacuum discharge device, a hollow electrode open at both ends, said electrode being provided with a plurality of heat radiating surfaces having a surface area of the same order of magnitude as the surface area of the electrode and extending outwardly from said electrode.
12. In a vacuum discharge device, an evacuated receptacle, a hollow electrode therein open at both ends, said electrode being provided with a plurality of heat radiating surfaces having a surface area of the same order of magnitude as the surface area of the electrode, and means operatively related to said heat radiating surfaces for supporting said electrode in said receptacle.
- In witness whereof, I have hereunto set my hand this 3rd day of March, 1919.
- SAUL DUSHMAN.
